UNITED STATES PATENT OFFICE.

JAMES ALEXANDER MOORE, OF WEIR, KANSAS, ASSIGNOR OF ONE-HALF TO JOHN YOUNG, OF WEIR, KANSAS.

HOOP-ROLLING DEVICE.

1,353,778.

Specification of Letters Patent. Patented Sept. 21, 1920.

Application filed February 16, 1920. Serial No. 359,048.

To all whom it may concern:

Be it known that I, JAMES A. MOORE, a citizen of the United States, residing at Weir city, in the county of Cherokee and 5 State of Kansas, have invented new and useful Improvements in Hoop-Rolling Devices, of which the following is a specification.

This invention relates to a toy in the 10 nature of a hoop rolling device, and the object of the invention is to provide a device of this character whereby a hoop may be rolled and whereby other movable parts may, at the same time, be actuated to give to 15 the rolling device the appearance of having a jumping motion simulating somewhat the running action of a jack rabbit or similar animal.

The invention consists of the features of 20 construction, combination and arrangement of parts, hereinafter fully described and claimed, reference being had to the accompanying drawing, in which:—

Figure 1 is a view in side elevation of the 25 device as employed in connection with a hoop.

Fig. 2 is a top plan view of the same.

In carrying my invention into practice I provide a hoop rolling device comprising a 30 preferably oblong rectangular frame 1 composed of longitudinal side plates 2 and 3 coupled by suitable connecting members 4, which rigidly join and hold them in spaced relation. The side plate 2 projects at its 35 forward end a short distance in advance of the forward end of the side plate 3 and carries at such end a laterally projecting hoop retaining hook 5, while the rear end of the side plate 2 projects a distance in rear of the rear end of the side plate 3 and is 40 properly shaped to provide a manipulating handle 6.

Arranged between the forward ends of the side plates 2 and 3 is a friction roll 7 45 carried by a transverse spindle 8, the ends of said spindle being journaled in and projecting through suitable openings formed in the side plates. The friction roll is adapted for bearing contact with the hoop 9 which 50 is adapted to be held and rolled by the actuating device. This hoop 9 is designed to be retained between the hook 5 and the roll 7 and to rest with the rear portion of its periphery in bearing contact with said friction roll, so that when the device is sup-

ported by being held in the hand of the operator, as shown in Fig. 1, and forward pressure is exerted through said friction roll upon the hoop, as the operator runs or walks, rolling motion in a forward direction 60 will be transmitted to the hoop in an obvious manner, while at the same time the friction roll 7 will be revolved.

The free end or bill of the hook 5 is arranged in suitably spaced relation to the 65 foreshortened forward end of the side plate 3 to provide a throat or entrance space 10, through which the hoop is adapted to be inserted and removed, the construction being such that the hoop may be easily disassociated from the actuating device whenever desired, while during the rolling action the 70 hoop will be held between the hook and friction roll against accidental displacement. The hook 5 is spaced a sufficient distance in 75 advance of the friction roll 7 to permit the hoop 9 to have a certain range or degree of forward and backward motion, during which it may move into and out of engagement with the friction roll, in order that 80 sufficient freedom of motion may be allowed to permit the hoop to travel over irregularities of surface without transmitting violent shocks or jars to the friction roll or other parts of the actuating device. 85

Motion simulating devices are arranged at each side of the frame, and each set of these devices comprises a circular crank disk 11 mounted upon the adjacent end of the spindle 8 and carrying a wrist pin 12 with 90 which is pivotally connected the forward end of a reciprocating bar or member 13. The rear end of this bar or member is provided with a longitudinal slot 14 slidably and pivotally engaging a headed pin or 95 stud 15 upon the adjacent side plate of the frame, the construction being such that when the roller 7 is revolved the crank disks 11 will be revolved therewith and the bars 13 will be given a backward and forward and upward and downward motion, the cranks and bars simulating to a certain extent the running motion of a jack rabbit or similar animal. The wrist pins 12 of the two crank disks 11 are arranged at diametrically opposite points so that the bars 13 will simultaneously move in reverse directions and so that ease of motion will be secured by the avoidance of dead centers. 100 105 110

From the foregoing description, the con-

2
struction and operation of my improved hoop rolling device will be readily understood, and it will be seen that a device of this kind is provided which is simple of construction and by means of which rolling motion may be imparted to the hoop which in turn will drive the friction roll, and that the friction roll will communicate motion to the side sets of motion simulating elements, which adds zest and interest to the operation of the device.

Having thus fully described my invention,

I claim:

1. A device of the character described comprising a frame having a manipulating handle, a hoop engaging friction roller on said frame, a laterally disposed hoop retaining hook arranged in spaced and coöperative relation to said friction roller to 15 movably hold a hoop in engagement with said friction roller, rotary elements at the opposite sides of the frame actuated by the friction roller, and reciprocatory elements at 20 the opposite sides of the frame actuated by 25 said rotary elements.
2. A device of the character described

comprising a frame having a manipulating handle, a hoop engaging friction roller on said frame, a laterally disposed hoop retaining hook arranged in spaced and coöperative relation to said friction roller to 30 removably hold a hoop in engagement with said friction roller, guide members on the frame, rotary crank disks actuated by the friction roller and provided with wrist pins, 35 and reciprocatory bars pivotally engaging said wrist pins and having slotted portions slidably and pivotally engaging said guide members.

3. A device of the character described comprising a frame having a manipulating handle, a hoop engaging friction roller on said frame, a hoop retaining device coöperating with said roller, guide members on the frame, rotary crank disks actuated by the 45 roller and provided with wrist pins, and reciprocatory bars pivotally engaging said wrist pins and having slotted portions slidably and pivotally engaging said guide members.

In testimony whereof I affix my signature.
JAMES ALEXANDER MOORE.
